UNITED STATES PATENT OFFICE.

ARTHUR W. WELLINGTON, OF WATERBURY, CONNECTICUT, ASSIGNOR TO THE CHASE COMPANIES, INC., OF WATERBURY, CONNECTICUT, A CORPORATION.

FLASH LIGHT OR BATTERY HAND LAMP.

Application filed May 14, 1921. Serial No. 469,482.

To all whom it may concern:

Be it known that I, ARTHUR W. WELLINGTON, a citizen of the United States, residing at Waterbury, in the county of New Haven 5 and State of Connecticut, have invented a new and useful Improvement in Flash Light or Battery Hand Lamps; and I do hereby declare the following, when taken in connection with the accompanying drawings 10 and the characters of reference marked thereon, to be a full, clear, and exact description of the same, and which said drawings constitute part of this application, and represent, in—

15 Fig. 1 a view in side elevation of a flashlight or battery hand-lamp constructed in accordance with my invention, showing the two terminal strips by broken lines.

20 Fig. 2 a view thereof in central longitudinal section.

Fig. 3 an enlarged detached sectional view of the cap or closure of the tubular lamp-case.

25 Fig. 4 a detached plan view of the shallow, flanged contact-cup which is insulated within the closure or cap of the tubular lamp-case.

Fig. 5 an edge view thereof.

30 Fig. 6 a detached plan view of the ring employed for the insulation of the contact-cup.

Fig. 7 an edge view thereof.

35 Fig. 8 a detached plan view of the insulating disk located within the case-cap or closure.

Fig. 9 an edge view thereof.

40 Fig. 10 a detached plan view of the lower terminal-strip, showing its clearance opening by which it is insulated from the switch-housing.

45 My invention relates to an improvement in that class of flashlights or battery hand-lamps which are constructed with particular reference to preventing short-circuiting and the consequent wearing out of the batteries in case the lamp is placed in a wire mail-basket or brought into contact with metal in such a way as to cause short-circuiting, the object being to produce a simple, convenient and reliable lamp of the character 50 described in which the metal cap serving as a closure for the lower end of the tubular lamp-case is permanently insulated from the battery located within the same.

With these ends in view, my invention 55 consists in a flashlight or battery hand-lamp having certain details of construction as will be hereinafter described and pointed out in the claims.

In carrying out my invention as herein 60 shown, I employ a wide terminal-strip 2 leading downward from the contact-rivet 3 of the switch which is located about midway the length of the tubular fibre lamp-case 4 and which consists of a housing 5 secured 65 by rivets 6, 7 and 8 to the case 4, a sliding contact-button 9 carrying a spring-contact 10 to engage with the contact-rivet 3 when the button is slid upward or forward, and a push-button 11 mounted upon the said 70 spring-contact 10. But I do not limit myself to using any one type of switch, that shown being of standard construction.

The lower end of the strip 2 is carried 75 downward through the case 4 and clasped over the edge thereof as at 12 so as to make contact with the annular flange 13 of a shallow sheet-metal contact-cup 14 insulated within the sheet metal cap or closure 15 which has its edge formed with rolled-in 80 threads to adapt it to be screwed upon a threaded sheet-metal assembling-collar 16 secured to the case 4 at a point just above the lower edge thereof as shown in Fig. 2. The said contact-cup 14 is insulated from 85 the cap 15 by means of an insulating ring 17 upon the upper edge of which its flange 13 rests as shown in Fig. 3. For fastening the cup 14 to the ring 17, the former is provided 90 upon its lower edge with two retaining-fingers 18 (Figs. 4 and 5), and the latter with an annular groove or rabbet 19 located within its lower edge as shown in Fig. 3, the said fingers being bent outward into the said 95 groove or rabbet below which the body portion of the ring extends for a sufficient distance to support the bottom of the cup 14 above the bottom of the cap, whereby the cup is insulated therefrom, whether or not an insulating disk 20 (Figs. 8 and 9) is interposed between them, as shown in the said Fig. 3. A spiral spring 21 located within the insulated contact-cup 14 electrically connects the battery 22 through the same, with the hooked end 12 of the terminal-strip 2. 100 As shown the spring 21 is secured to the cup 14 by the passage of its lower coil through loops 23 struck up from the bottom 105

thereof as best shown in Figs. 3 and 4, but other means for securing the spring to the cup may be resorted to, if desired.

Under the construction above described, 5 the strip 2 is entirely insulated from the metal cap 15 and assembling collar 16 so that no circuit can be accidentally closed through the lower end of the lamp. Moreover the cup 14 with its annular flange 13, 10 insures contact with the hooked end 12 of the strip 2 in any rotated position of the cap or closure 15, i. e., whether the same is screwed more or less upon the said assembling-collar in assembling the lamp provided only that some portion of the flange 13 of the cup 14 is seated against the end 12 of the strip 2.

The upper contact strip 24 leads from the rivet 7 of the housing 5, and is clasped over 20 the upper edge of the case 4 as at 25 in position to be engaged by the inwardly turned flange of the upper assembling collar 26 which is secured to the case by rivets 27 and formed with rolled-in threads for the application of the flanged and threaded ring 28 by means of which the lens 29 is held 25 down upon the reflector 30 the flanged upper edge of which rests upon the inwardly turned flange of the collar 26. The parts 30 now being described are of standard construction, the reflector 30 receiving a lamp 31 the downwardly projecting stem 32 of which is engaged by the pole 33 of the battery 22 which is constantly pushed upward 35 for the maintenance of this contact by the spring 21 aforesaid.

By insulating in the manner described the exposed metal parts of the lower end 40 of the lamp I prevent short circuiting in case the same is thrown into a wire basket or a metal bridge is established in some way between the metal parts at the upper and lower ends of the lamp. This result I effect 45 through the medium of the insulated contact cup 14 and associated parts. Now to prevent short circuiting and the wearing out of the battery by the accidental connection of the switch housing 5 with the exposed metal parts at the upper end of the lamp, I 50 form a clearance opening 35 in the wide terminal strip 2 so as to entirely insulate the said strip from the housing rivet 6 which the strip passes on its way to the contact-rivet 3. By this simple expedient of 55 providing the terminal-strip 2 with a clearance-opening, I preclude the chances of short-circuiting through the switch-housing 5.

My invention is not concerned with the 60 detailed construction of the lamp except in so far as I provide means for insulating the exposed metal parts at its lower end from the lower end of the lower terminal strip and insulating the housing of its switch 65 from the upper end of the said strip. In

other respects the lamp may be of standard construction, as may be the switch, as already explained. If desired, a metal case or even a cardboard or glass case, may be used in place of a fibre case. In the event 70 of using a metal case, the lower terminal-strip would be insulated therefrom. As already stated, the disk 20 may be dispensed with, if desired.

I claim:

1. In a battery hand-lamp, the combination with a tubular case, of a switch mounted thereupon, a terminal-strip leading from the said switch to the lower end of the case and bent over to the edge thereof, a metal cap 80 for the closure of the lower end of the case, a contact-cup insulated within the said cap and adapted to engage with the end of the said strip, and means for electrically connecting a battery located within the said 85 case to the said cup.

2. In a battery hand-lamp, the combination with a tubular case, of a metal cap for the closure of the lower end thereof, a terminal-strip located within the case and fastened to the lower end thereof, a contact cup located within the said cap and normally engaging with the said strip in any rotated position of the cap, and an insulating ring interposed between the cap and the cup for 95 the insulation of the latter.

3. In a battery hand-lamp, the combination with a tubular case, of a metal cap for the closure of the lower end thereof, a terminal-strip located within the case and fastened to the lower end thereof, a contact cup located within the said cap and normally engaged by the said strip, and an insulating ring mounting the said contact cup and supporting the same above the bottom of the 100 cap.

4. In a battery hand-lamp, the combination with a tubular case, of a metal cap for the closure of the lower end thereof, a terminal-strip located within the case, a flanged 110 contact-cup located within the cap and formed with retaining-fingers, an insulating ring mounting the said cup and engaged by the fingers thereof, whereby the cup and ring are secured together, and means for electrically connecting the cup and battery when the latter is in place within the case.

5. In a battery hand-lamp, the combination with a tubular case, of a metal cap for the closure of the lower end thereof, a terminal-strip located within the case, an insulating-ring located within the said cap and having its lower end formed with a rabbet, and a flanged contact-cup mounted in the said ring in position to engage with the 125 said strip and formed upon its lower edge with retaining-fingers which are entered into the said rabbet for holding the cup and ring together.

6. In a battery hand-lamp, the combina- 130

tion with a tubular case, of a metal cap for the closure of the lower end thereof, a terminal-strip, an insulating-ring located within the said cap, a flanged contact-cup 5 mounted in the said ring upon which its flange rests and formed with loops and retaining-fingers which latter are engaged with the ring for securing the cup and ring together, and a spring located within the 10 cup and having its lower coil passed

through the loops thereof, the said spring serving to connect the cup with the battery and to hold the battery in place.

In testimony whereof, I have signed this specification in the presence of two sub- 15 scribing witnesses.

ARTHUR W. WELLINGTON.
